UNITED STATES PATENT OFFICE.

WILLIAM M. SCOTT, OF TREDYFFRIN TOWNSHIP, CHESTER COUNTY, PENNSYLVANIA.

SWITCHING APPARATUS.

1,251,294.

Specification of Letters Patent. Patented Dec. 25, 1917.

Application filed June 22, 1915. Serial No. 35,700.

To all whom it may concern:

Be it known that I, WILLIAM M. SCOTT, a citizen of the United States, residing at Tredyffrin township, in the county of Chester and State of Pennsylvania, have invented a new and useful Switching Apparatus, of which the following is a specification.

My invention relates to electrical control apparatus, and particularly to apparatus for switching or controlling heavy electric currents such as used in electric lighting and electric power practice.

My invention resides in a system comprising a plurality of switches or circuit breakers which may be operated either manually or by power, with suitable means for insuring that they shall not simultaneously be in normal, generally closed, position, but allowing all to be in abnormal, generally open, position, such means comprising suitable electrical and mechanical interlocks or controls hereinafter described.

In another of its aspects my invention comprises such switches or circuit breakers with means insuring that the switches or breakers of a given circuit shall be closed only in a predetermined sequence.

In another of its aspects my invention comprises a plurality of switches or circuit breakers with each or each group of which is associated an additional switch or circuit breaker, with means insuring that these additional switches or circuit breakers shall never be simultaneously in normal, generally closed, position, but allowing them to be simultaneously in abnormal, generally open, position; and means for tripping or opening either or any of such additional switches or breakers which in opening cause the tripping or opening of the other switches or circuit breakers; and also in means associated with the operating mechanism for these additional switches or circuit breakers for releasing or rendering operable the operating mechanisms of the other switches or breakers.

As to another of its aspects my invention resides in switching mechanism for connecting a generator with either of a plurality of circuits or sets of buses, with an equalizer switch for each circuit or set of buses, which equalizer switches are prevented from being simultaneously closed, though all may be open, together with means allowing only that switching mechanism to close circuit with a circuit or set of buses when the cor-

responding equalizer switch has been closed; and in such a system means insuring opening of all the switches or circuit breakers when either equalizer switch opens.

My invention resides also in circuit arrangements and connectitons for controlling apparatus such as above referred to.

My invention resides also in other features hereinafter described and claimed.

For an illustration of some of the forms my invention may take, reference is to be had in the accompanying drawings, in which:

Figure 1 is a side elevational view of two equalizer switches or breakers and their operating mechanism.

Fig. 2 is a side elevational view, on enlarged scale, of part of the tripping mechanism.

Fig. 3 is a side elevational view, on enlarged scale, of a part of similar tripping mechanism.

Fig. 4 is a side elevational view, on enlarged scale, of manual operating mechanism illustrated in Fig. 1.

Fig. 5 is a side elevational view of a modification of similar manual operating mechanism.

Fig. 6 is a side elevational view, with motor operating means omitted, of the main switches or circuit breakers.

Fig. 7 is a front elevational view of a complete set of switching mechanism with their driving motors.

Fig. 8 is a top plan view of the operating mechanisms for the equalizer switches and for one set of main switches.

Fig. 9 is a side elevational view, partly in vertical section, of apparatus shown in Fig. 8.

Fig. 10 is a fragmentary side elevational view of part of the actuating mechanism.

Fig. 11 is a fragmentary side elevational view illustrating means for preventing engagement of a worm with its gear under certain circumstances.

Fig. 12 is a fragmentary view illustrating structure of the localizing switch.

Fig. 13 is a fragmentary view illustrating structure of a motor control switch.

Fig. 14 is a diagrammatic view of circuit arrangements for effecting the various controls.

Fig. 15 is a fragmentary view illustrating means for locking the operator's control switch.

MOTORIC TURBINE GENERATOR CONTROL

Fig. 16 is a view, partly in section and partly in elevation, of part of the interlock mechanism.

Referring first to Fig. 14 for a brief description of one of the applications of my invention, G represents a compound-wound direct current generator having the armature *a*, shunt field *b* and series field *c*, which is to be connected either with the buses or circuit conductors *d* and *e* or the buses or circuit conductors *f* and *g*, of which *d* and *f* are the positive buses or conductors and *e* and *g* are the negative buses or conductors. With the buses *d* and *e* is associated the equalizer bus *h*, and with the buses *f* and *g* is associated the equalizer bus *i*.

The purpose of the apparatus is to close one of the equalizer switches or breakers E between the common terminal of the armature *a* and series field *c* and the equalizer bus *h*, and thereafter close the positive pole switch or breaker A between the positive terminal of the generator G and the bus *d* through series field *c* and thereafter the negative pole switch or breaker A¹ between the negative terminal of the generator G and the negative bus *e*. Or to close the equalizer connection between the generator G and the equalizer bus *i* through the equalizer switch or breaker E¹ and thereafter the positive pole switch or breaker B and thereafter the negative pole switch or breaker B¹ with the positive and negative buses *f* and *g*, respectively. And in this system means are provided for tripping all of the main switches A, A¹, B and B¹ when either of the equalizer switches E or E¹ is tripped or opened and vice versa, together with suitable electrical and mechanical interlocks or controls for insuring that only one of the equalizer switches may at any time be closed, and that at any such time only the proper associated pair of the main switches or breakers may be closed.

Referring now to Fig. 1, the equalizer breakers E and E¹ are shown disposed one vertically above the other upon the base or switchboard 1 of marble or other suitable insulating material.

Each of the equalizer switches or breakers may be of any suitable structure and is here shown to comprise the stationary main contact terminals 2 and 3 secured upon the switchboard 1, the contact 2 of the switch E connecting with the equalizer bus *h* and the contact terminal 2 of the other switch E¹ connecting with the equalizer bus *i*. The lower terminals 3 of both switches are connected to the conductor or equalizer lead 4 connecting to one terminal of the series field of the generator G. Adapted to engage and bridge the terminals 2 and 3 is the movable laminated contact member 5 pivoted in the housing 6 and operated by suitable

toggle or other mechanism 7 comprising the operating lever 8 pivoted to the housing at 9. The latch 10 serves to lock the switch in closed position, and latch actuating mechanism 11 serves to trip the latch. The latch actuating mechanisms 11 of the upper and lower switches are tied together by the rod 12 to cause their simultaneous actuation by the tripping magnet 13 having the armature 14 connected by link 15 to the actuator 11 of the lower breaker.

Each switch may be provided with the stationary and movable metallic shunt contacts 16 and 17, and the stationary and movable carbon shunt contacts 18 and 19 for taking the arcs occurring at circuit rupture.

Below the switches E, E¹ upon the switchboard 1 is disposed their operating electric motor M on the upper end of whose armature shaft is secured the gear 20, Fig. 8, meshing with and driving the gears 21 and 22 which drive through universal joints 23 their respective worms 24 and 25 adapted to mesh respectively with the worm gears 26 and 27 driving respectively the cranks 28 and 29 to which are pivoted at 30 and 31 the connecting rods 32 and 33, of which 32 is pivoted at 34 to the operating lever of the upper switch E and 33 is pivoted to the operating lever 8 of the lower switch E¹. To the upper end of each worm shaft is pivoted a toggle link 35 pivoted to the toggle link 36 which is pivoted to the housing at 37. And connected by pin and slot connection to each toggle link 36 is the core 38 of a solenoid, solenoid 39 for worm 24 and solenoid 40 for worm 25. When either of the solenoids is energized it attracts its core 38 upwardly extending the toggle and thereby shifting its worm into mesh with its worm gear, and upon deenergization the core falls and breaks the toggle and withdraws the worm from mesh with its gear.

At 41 is pivoted the bar or beam 42 whose ends 43 and 44 are disposed in the paths of travel of the upper ends of the shafts of worms 24 and 25, so that as one worm is thrown into mesh with its gear it actuates the lever 42 to cause the other end thereof to positively withhold the other worm from mesh with its gear, this operation preventing both worms from being simultaneously in mesh with their gears.

On the gear 26 is a lateral arc shaped projection 45 having the inclined or cam surface 46 at its one end and at its other end the square shoulder 47.

On the gear 27 is a similar lateral projection 48 having the cam edge 49 and a square shoulder at its other end.

Between the two gears 26 and 27 is the laterally movable pin 50 normally held in its central position by a spring 51. As shown in Fig. 16, the spring 51 is disposed between the washers 51^a each slidably, re-

spectively, along the pin 50, with the result that when the pin 50 is moved longitudinally, one or the other of the washers 51^a will engage one or the other of the housings 6^a and compress the spring, which, after release of the pin 50, will expand and restore the pin 50 to its normal mid-position. When the gear 26 is rotated by the motor driven worm 24 the end 52 of the pin 50 is shifted laterally by the cam 46, thus thrusting the other end 53 of the pin 50 into the path of travel of the square end of the projection 48, thus positively preventing the rotation of the gear 27; and similarly, when the gear 27 is rotated the end 53 of the pin 50 is shifted laterally by the cam 49 to bring the end 52 in front of the shoulder 47 to positively prevent rotation of gear 26.

A pin 54 is carried by the gear 26 and is adapted to engage the under side of the lever 55 pivoted at 37 to lift the lever 55 and the rod 56 attached thereto and extending over to the operating mechanism of the breaker A. Similarly a pin 57 is carried by the gear 27 and is adapted to engage the under side of the lever 58 pivoted at 37 and attached to the rod 59 extending across to the operating mechanism of the breaker B.

Pivoted to the upper end of the shaft of each of the worms 24 and 25, as well as the worms associated with the breakers A, A¹, B and B¹, is a link 60, Fig. 1, for shifting the movable contact 61 of the localizing switch away from the stationary contact 62 and into engagement with the stationary contact 63. As shown in Fig. 12, the movable contact 61 may be in effect two yielding buttons 61 adapted to engage respectively the stationary contacts 62 and 63. When a worm is thrust into engagement with its gear the contact 61 leaves the stationary contact 62 and engages stationary contact 63.

Operated by each of the worm gears of each of the switches or breakers through crank 64, rod 65, and lever 66 is the movable contact 67 of a motor control snap switch co-operating with the stationary contact 68. As shown in Fig. 13 the movable contact may comprise a yielding button 67 adapted to engage the stationary contact 68, a plunger 69 being thrust in opposition to the spring 70 when the switch is closed. Each of these motor switches is closed by the opening of the large switch or breaker which it controls and opens upon the completion of the closing movement of such large switch or breaker.

The gear locking pin 50 carries near its opposite ends the collars 71 and 72, shown also in Fig. 16. When the gear 27 through its cam 49 shifts the pin 50 laterally to bring its end 52 into position to prevent rotation of gear 26 the cam or shoulder 71 is brought

into the path of the arm or lever 73 carried on the upper end of the shaft of the worm 24, preventing the worm 24 from being shifted into mesh with its gear 26 should the solenoid 39 become accidentally energized. The relation of the collar 71 and lever or arm 73 is indicated in Fig. 11. Similarly, the shaft of the worm 25 carries on its upper end an arm or lever 74 into whose path the collar 72 is shifted when the gear 26 rotates and by its cam 46 shifts the pin in opposite direction, to prevent shifting of worm 25 into mesh with gear 27 should the solenoid 40 be accidentally or improperly energized.

In Fig. 6 the switches or breakers A, A¹ are shown in open position while the switches or breakers B and B¹ are shown in closed position.

Each of the breakers A and A¹ may be of any suitable structure and is here shown to comprise the stationary terminal blocks 75 and 76 adapted to be engaged and bridged by the movable laminated contact members 77 each operated by toggle mechanism 78 comprising the operating lever 79. The terminal 75 of the breaker A is connected to the positive bus d and the terminal 75 of the breaker A¹ is connected to the negative bus e.

The breakers B and B¹ may be of structure similar to A and A¹ and comprise the terminal blocks 80 and 76 adapted to be engaged and bridged by the laminated bridging members 81 operated by similar toggle mechanism including the operating levers 82. The terminal 80 of the breaker B is connected to the positive bus f and the terminal 80 of breaker B¹ is connected to negative bus g. The lower main terminals 76 of breakers A and B are one continuous conductor, as are also the lower terminals 76 of breakers A¹ and B¹.

Each of the circuit breakers, A, B, A¹ and B¹ is provided with a latch or dog 83 for restraining it in the circuit closing position. The vertically extending bars 86^a and 86 together with the respective pairs of bell crank levers 95^a, 95^a, and 95^b, 95^b interconnect the latch actuators 84 and 85 in the manner hereinafter described so that the opening of either upper breaker will cause the opening of the corresponding lower breaker and vice versa the opening of either lower breaker will cause the opening of the corresponding upper breaker. The bar 84 may be actuated by the overload tripping magnet whose energizing coil is represented diagrammatically at 87, Fig. 14. The armature 88 of this overload tripping magnet is adapted in the well known manner to actuate the bar 84, upon flow of excess current; this will cause the tripping of whichever of the upper switches or breakers may be closed, and by the resulting movement communicated through the corresponding bell crank levers 95^a or 95^b and the associated vertical

rod 86^a or 86 will also trip whichever of the lower switches or circuit breakers is closed. The bar 85 connecting the latch actuators is adapted to be actuated by the armature 88^a of an overload magnet indicated at 87^a in Fig. 14, or through rod 89^a of the reverse energy flow tripping magnet comprising the shunt coils 90 co-operating with the magnet 91 energized by the current flowing through the lower stud 92 connecting with the lower contact 76 of the lower breakers or switches. In Fig. 14 93 represents the current coil of this reverse energy flow of tripping mechanism and the shunt or potential coils are indicated at 90.

Referring to Figs. 1, 2, 3 and 7, there is pivoted at 94 on the housing 6 of the upper and lower equalizer switches E and E¹ a bell crank lever 95 having a head 96 adapted to be struck as the switch E or E¹ opens. This communicates movement to the bar 97 which extends across to the breakers A or A¹, Fig. 7, and is there adapted to actuate the bell crank lever 95^a and through it the bar 84 or the bar 85, depending upon which of the breakers E or E¹ opens, to trip any of the breakers A, A¹ or B, B¹ which may be closed. These parts are shown in Fig. 2 and Fig. 3.

There is a lever 95^a at the left of each of the breakers A, A¹ and a similar lever 95^b at the right of each of the breakers B, B¹. The lower ends of these levers 95^a are connected together and pivoted to the vertical rod 86^a; levers 95^b are connected in an identical manner, so that upon the opening of either upper breakers the associated head 96 will be engaged and thereby transmit a movement through rod 86 or 86^a to the latch actuators of the lower breakers; and vice versa, when either of the lower breakers opens it engages the associated head 96 to transmit a movement through the rod 86 or 86^a to actuate the latch actuators of the upper breakers to trip them.

45 The main switches, A, A¹ are actuated by the motor M¹, and the breakers or switches B and B¹ are actuated by the motor M², Fig. 7.

Pivoted at 98 to the operating lever 79 of breaker A is a vertically extending rod 99 connected to a crank upon the worm gear 100; and pivoted to the operating lever 79 of the lower breaker A¹ is a vertically extending rod 101 connected to a crank driven by worm gear 102. Similarly, the operating lever of the upper breaker B is connected by rod 103 with a crank on worm gear 104; and the operating lever of the lower breaker B¹ is connected by rod 105 with a crank upon the worm gear 106.

As shown in Fig. 8, the motor M¹ drives the gear 107 which in turn drives the gears 108 and 109 driving respectively the worms 110 and 111 controlled, as in the case of worms 24 and 25, by solenoids 112 and 113.

Similarly the motor M² drives worms co-operating with gears 104 and 106 and controlled by solenoids 114 and 115, the latter indicated only in Fig. 14. Each of the four worms and worm gears for the breakers A, A¹, B and B¹ is normally locked by a hooked lever 116 as indicated in Figs. 8 and 10. In Fig. 10 is shown the worm 110 and the worm gear 100 associated with the breaker A. The lever 116 has a hook 117 engaging a member at the upper end of the shaft 110 preventing the worm 110 being shifted into mesh with the gear 100; and the lever 116 has the second hook 118 engaging the lug 119 on the gear 100 preventing its rotation. The hooked lever 116 is actuated by the bar 56 which is actuated to lift the lever 116 after predetermined extent of movement of the gear 26 of the equalizer switch E. A similar hooked lever 124 is actuated by the rod 59 to release the worm and the gear 104 of the switch B after predetermined movement of the gear 27 of the equalizer switch E¹.

After predetermined movement of the gear 100 the pin 120 thereon raises the lever 121 which actuates the bar 122 which thereupon lifts the hooked lever 123 to release the worm 111 and the gear 102 of the lower breaker A¹, and similarly, after predetermined movement of the gear 104 it transmits a lifting movement to the locking lever 125 to release the worm and the worm gear 106 of the breaker B¹.

Pivoted concentrically with each of the six worm gears and secured thereto is a member 126, Fig. 4, by which it may be manually actuated by the manually operated lever 127, having the handle grip 128 and independently pivoted to the base or housing 129. Pivoted on the operating lever 127 at 130 is the dog 131 adapted to engage the member 126. When it is desired to manually close any one of the switches independently of its motor, lever 127 is raised by the operator whereupon the dog 131 will fall by gravity to the engaging position shown in Fig. 4. In depressing the lever 127 the associated worm gear will be actuated and thereby transmit closing movement through the connecting rod to the associated switch or breaker. As the closing movement is completed the plunger 132, carried by the lever 127, and pressed forwardly by the spring 133 engages a suitable stop, as 134, Fig. 1, thereby compressing the spring 133 as the main switch or breaker is closed. Upon releasing the handle 128 the spring 133 expands and returns the lever 127 a short distance, whereupon the dog 131 will rotate by gravity about its pivot 130 to a position free from the member 126.

As a modification of this manual operating means a structure similar to that illustrated in Fig. 5 may be employed. In this

case the lever 127 is provided with an elongated slot 135. The member 126^a, mounted upon the worm gear pivot and secured to the worm gear, has a notch 136 in which is 5 adapted to engage the lug 137 rigidly carried by the lever 127. In the position shown in Fig. 5 the lever 127 has been raised and pushed toward the left, as allowed by the slot 135, and the member 137 engaged in notch 10 136. By downward movement the associated switch or breaker is closed. At the completion of the movement and the removal of the operator's hand the spring 133 returns the lever 127 slightly and lifts the lug 137 free 15 of the notch 136, whereupon the lever 127 falls by gravity, as allowed by the slot 135, to disengaged position.

Referring again to Fig. 14, the localizing switches 138, 139, 140, 141 and 142 are similar to the localizing switch 61, and are controlled respectively by the solenoids 40, 112, 20 113, 114 and 115, through their worm shifting toggles. And the motor control switches 143, 144, 145, 146 and 147 are similar to 25 motor control switch 67 and are similarly actuated by the breaker actuating mechanism.

The operator's control switch D includes the movable contact 148, normally centered in open position by the springs 149, and which may be moved by the handle 150 to the left to engage contacts 151, 152 and 153 and to the right to engage contacts 154, 155 and 156. As shown in larger scale in Fig. 30 15, the movable member of this control switch is provided with a notch 157 in which is adapted to engage the lug 158 on the armature 159 of electro-magnet 160 when the latter is deenergized or is subject to 35 normal voltage. The magnet 160 is, however, sufficiently energized to withdraw its armature from the above described engagement only when subjected to the normal voltage of the generator with which it is 40 connected, such connection being made only when breakers A¹ and B¹ are both in the open position, in which position they allow the circuit of the magnet coil to be completed through the plunger switches 172 and 45 183; therefore whenever the generator G is 50 at normal voltage and the switches A¹ and B¹ are both open the armature 159 is held attracted to unlock the movable member of the switch D which may then be actuated by 55 the operator.

The operation is as follows:

With the parts in the positions indicated, the motor M has closed the equalizer switch E¹ and the motor M² has closed the main 60 switches or breakers B, B¹ in which relation the generator G is connected to the buses f, g and i.

If it is desired to open these switches or breakers the operator closes the switch 161 65 whereupon current will flow from the con-

ductor 162 connecting with any suitable source of energy, through the switch 161, conductor 163, switch 164, which is closed when the switch E¹ is closed and which opens when E¹ opens, through conductor 70 165, tripping coil 13 to the other conductor 166 of the supply circuit. This energizes the trip coil 13 whereupon the breaker E¹ is tripped. The switch E¹ accordingly opens and in so doing engages the associated head 96 of lever 95 which thereupon actuates the bar 97 which in turn actuates the bar 85 to trip the lower breaker B¹ which in opening engages the similar associated head 96 of lever 95 to actuate the 80 rod 86 which accordingly actuates the rod 84 of the upper breakers to trip the upper breaker B.

In opening, the switch E¹ has opened switch 164 and also switches 167 and 168 85 and has closed switch 169. In opening, switch B has opened switches 170 and 171. In opening, switch B¹ has allowed closure of switch 172, and has opened switches 173 and 174.

When switch E opens, switches 175, 176 and 177 are opened, and switch 178 is closed. When switch A opens switches 179 and 180 are opened. When switch A¹ opens switches 181 and 182 are opened, and switch 90 183 is closed.

Switches 172 and 183 are in series with each other and resistance 160^a and the locking magnet 160 which can therefore be energized only when both switches A¹ and B¹ 100 are open, in which case the coil 160 is connected across the terminals of the generator G, which if at normal voltage, sufficiently energizes the magnet 160 to unlock the operator's lever 150. In other words, the operator's switch D can be operated only when both switches A¹ and B¹ are open and when the generator G is operative at normal voltage. 105

If, now, it is desired to connect the generator G with the buses d and e, the operator's switch handle 150 is shifted toward the left, bringing contact 148 into engagement with contact 151, whereupon current will flow from supply conductor 162 to the 115 contact 148, thence through contact 151 and conductor 184 through switch 169, which is now closed because switch E¹ has been opened, through the localizing switch 61, solenoid 39, motor control switch 67, and 120 the motor M to conductor 166. This energizes the solenoid 39 and starts the motor M which rotates the worm 24 which is shifted into mesh with gear 26 by the solenoid 39. As the worm 24 is shifted into 125 mesh with its gear the localizing switch 61 is transferred to contact 63, making connection with conductor 162 independently of the operator's switch, which now loses control of the motor M. The gear 26 is accord- 130

80 previous when switch 140 is normally rotated and it actuates the rod 32 downwardly and moves the equalizer switch E to circuit closing position where it is latched. In reaching circuit closing position the motor switch 6 is opened thereby deenergizing the motor M and the solenoid 39, the core of the latter falling and breaking the toggle and withdrawing the worm 24 from mesh with gear 26 and restoring the localizing switch 61 to normal position. 85 As the gear 26 is rotated in the closing movement described it shifts the pin 20 to lock the gear 24 against movement and to bring the collar 22 into position to prevent movement of the worm 25 into mesh with gear 26. The pin 54 on gear 26 after predetermined movement of the latter lifts the lever 55 to actuate the rod 56 which accordingly lifts the locking or hooked lever 116 to unlock the gear 100 and the worm 119 of the main positive switch A. The continued movement of the operator's lever 140 brings the contact 148 into engagement with contact 152 whereupon current will flow 90 from conductor 162 through the contact 148, the contact 152 and conductor 185 through switch 149 which is now closed because the switch E has been closed, thence through conductor 186 through the localizing switch 139, solenoid 112, motor switch 144, and motor M to conductor 166, thus energizing the solenoid 112 and the motor M with the result, by operation similar to that previously described, that the worm 119, now freed from locking lever 116, is brought into mesh with and drives gear 100 which is now also freed from lever 116, the gear 100 operating the rod 99 to close and latch the main positive breaker A followed by the opening 95 of the motor switch 144, and the return of localizing switch 139 to normal and deenergization of solenoid 112 and motor M. After predetermined movement of the gear 100 its pin 120 lifts the lever 121, thereby actuating the bar 122 to raise the locking lever 123 to free the worm 111 and the gear 102. The continued movement of the contact 148 brings conductor 152 into communication with contact 153 from which current flows over conductor 187 through switch 179 which is now closed because the breaker A has been closed, through conductor 188, the localizing switch 140, solenoid 113, and motor switch 145, thereby energizing the solenoid 113 and motor M with the result that the worm 111 is shifted into mesh with and drives gear 102, which accordingly actuates the rod 101 to close and latch the lower negative breaker A'. At the end of this closing movement of breaker A' the motor switch 145 is opened, deenergizing motor M and solenoid 113, and returning localizing switch 140 to normal position. Upon release of the operator's switch 140 it returns 100 to normal position indicated, where it is

locked by lug 148 because the circuit of the coil 160 is broken at switch 183 which has been opened by the closure of the switch A.

These switches, so closed, may be opened by pressing the button or switch 161 whereupon the tripping coil 13 will again be energized, but in this instance through now closed switch 176. The tripping magnet 13 will actuate the vertical tripping rod 12 to trip the upper equalizer switch E which in opening will engage the associated heat 96 on lever 95 and through the upper rod 97 communicate a tripping movement to the upper breaker A which in opening communicates movement through rod 86 to latch actuator 85 to trip the lower breaker A'. 105

Similarly when the switch E is closed and the tripping coil 13 is energized switch E will be tripped and will open and in opening the lower rod 97 will be actuated to communicate a tripping movement to the rod 85 by which the lower switch B' is tripped which latter in opening commands through the rod 86 a tripping movement to the tripping mechanism of the upper switch or breaker B. 110

On upon overload, the overload coil 87 or 87' will trip the upper breaker A or the lower breaker A' and through the rod 88 the other breaker of the pair, or upon occurrence of reverse energy flow the coil 93 and 99 will cooperate to trip lower breaker A' which will trip the upper breaker through the rod 86. Such automatic tripping of the breakers, as A, A', leaves the corresponding equalizer switch E closed and this can be tripped only by pushing the button or switch 161. But if it should be attempted to close the breakers B, B' while the equalizer switch E remains closed, the energization of the motor M will be prevented because the switch 178 is open, when switch E is closed, the switch 178 being in series with the circuit controlled by the contact 154 of the operator's switch. The motor M cannot be energized for closing the equalizer E, which controls the subsequent closure of switches B and B' until the switch E is tripped open and thereby close switch 178. 115

Similarly when the breakers A and A' are open and B and B' are closed and there occurs an overload, reversal of energy flow or other condition to which the switches are to respond, one of the switches, either B or B', will first be tripped and in opening communicate through the rod 86 a tripping movement to the other. 120

Similarly, assuming all the switches and breakers open, if it is desired to close switches or breakers E, B and B' the operator's switch is moved toward the right, bringing contact 148 into engagement with contact 154, whereupon current flows from supply conductor 162, through contacts 148 125

and 154, conductor 189, switch 178, conductor 190, through localizing switch 138, solenoid 40, motor switch 143, which latter has been closed by the opening movement of the 5 switch E, and motor M to conductor 166, energizing motor M and solenoid 40 causing engagement of worm 25 with gear 27 which is then driven by the motor M to close the equalizer switch E¹ through rod 33. The 10 closure of the switch E¹ is accompanied by the closure of the switch 168 and the opening of the switch 169, together with the closure of the switch 164, controlling the circuit of the tripping magnet 13.

15 As the switch E¹ reaches closed position the localizing switch 138 is restored to normal position and the motor switch 143 is opened.

During this closing movement the gear 27 20 has actuated the pin 50 to lock the gear 26 and to prevent operation of worm 24 by its solenoid 39. And during this closing movement of switch E¹, the gear 27 after predetermined movement thereof causes pin 57 to 25 lift lever 58 to actuate rod 59 extending over to the operating mechanism of breaker B where it lifts the hooked lever 124 to unlock the gear 104 and its associated worm.

As the contact 148 engages contact 155 30 current will flow from the conductor 162 through these contacts and through conductor 191 through the now closed switch 168, conductor 192 through the localizing switch 141, solenoid 114, and motor control switch 35 146, which has been previously closed by the opening of breaker B, and through motor M² to conductor 166, energizing the solenoid 114 and motor M² causing the gear 104 to be driven by its worm to actuate the rod 103 to 40 close the positive pole breaker B. As breaker B is closed switches 170 and 171 are closed.

After predetermined movement of gear 104 in closing breaker B a pin thereon, similar to pin 120 of gear 100, actuates a lever similar to lever 121 to actuate a rod similar to rod 122 to raise the locking lever 125 to free the gear 106 and its associated worm.

Upon further movement of the operator's 50 lever to bring contact 148 into engagement with contact 156, current flows through these contacts from conductor 162 and thence through conductor 193, switch 170, conductor 194, through the localizing switch 55 142, solenoid 115, motor switch 147, which latter has been closed by the opening movement of breaker B¹, and thence through motor M² to conductor 166, energizing the solenoid 115 and motor M² to cause gear 60 106 to be driven by its worm for actuating rod 105 to close the breaker B¹. The operator's switch D then returns to normal position under influence of the springs 149 and is there locked by detent 158 because 65 154 the circuit of electro-magnet 160 is broken

by switch 172 opened by the closure of switch B¹.

Briefly stated, an equalizer switch must first be closed, then the positive and negative switches or breakers of a pair are closed 70 in the order named; and as the equalizer switch is closed, the other equalizer switch is prevented from closure by the pin 50 and collar 71 or 72 preventing rotation of the operating gear for the other equalizer 75 switch and preventing operation of the associated worm; and the operating mechanism of the positive main breaker remains locked, by locking its gear and worm which are unlocked after predetermined movement of 80 the equalizer switch gear; and after predetermined movement of the main positive switch operating gear the gear and its associated worm for the negative breaker of 85 the pair are unlocked. In addition to these mechanical features, the closure of an equalizer switch is accompanied by the opening of a switch in the control circuit of the other equalizer switch, preventing energization of the worm shifting solenoid and the 90 closure of the equalizer switch is accompanied by the closure of a switch in the control circuit for the positive main breaker; and closure of the main positive breaker closes a switch in the controlling circuit of 95 the main negative breaker.

When the equalizer switch E is closed a circuit is closed from conductor 162, through resistance 195, indicating lamp L¹, conductor 196, switch 175, conductor 197, 100 to conductor 166. The glowing of the lamp L¹ therefore indicates the closure of the equalizer switch E. When the main positive breaker A is closed a circuit is closed from conductor 162, through resistance 198, 105 lamp L², conductor 199, switch 180, conductor 200, to conductor 166 causing the lamp L² to glow and indicate closure of main positive breaker A. When breaker A¹ is closed a circuit is closed from conductor 162 110 through resistance 201, lamp L³, conductor 202, switch 181 to conductor 166 causing lamp L³ to glow and indicate closure of breaker A¹. When equalizer switch E¹ is closed, a circuit is closed from conductor 115 162, through resistance 195, lamp L⁴, conductor 203, switch 167 and conductor 204 to conductor 166 causing lamp L⁴ to glow and indicate closure of switch E¹. When breaker B is closed a circuit is closed from conductor 162 through resistance 198, lamp L⁵, conductor 205, switch 171, and conductor 206 to conductor 166 causing the lamp L⁵ to glow and thereby indicate closure of breaker B. When breaker B¹ is closed a circuit is 120 closed from conductor 162 through resistance 201, lamp L⁶, conductor 207, switch 174 and conductor 208 to conductor 166, causing the lamp L⁶ to glow and indicate closure of breaker B¹. 125 130

From the positive terminal of the generator G there is a circuit through the conductor 209, resistance 210, lamp L, conductor 211, to the negative terminal of the generator G, with the result that the lamp L glows when the generator is alive or operative and indicates that condition.

What I claim is:

1. The combination with a plurality of 10 main switches, of a motor, a disengageable mechanical connection between said motor and each of said main switches for moving the same to normal position, a pair of motor control switches for each of said main 15 switches, one control switch of each of said pairs closed when one of said main switches is in abnormal position, and the second control switch of a pair connected in series with the other control switch of the pair 20 and closed when another of said main switches is in abnormal position, whereby said motor cannot be energized to actuate one of said main switches to normal position when another of said main switches is 25 in normal position.

2. The combination with a plurality of main switches, of a motor, a disengageable mechanical connection between said motor and each of said main switches for moving 30 the same to normal position, a pair of motor control switches for each of said main switches, one control switch of each of said pairs closed when one of said main switches is in abnormal position, the second control 35 switch of a pair connected in series with the other control switch of the pair and closed when another of said main switches is in abnormal position, whereby said motor cannot be energized to actuate one of said main 40 switches to normal position when another of said main switches is in normal position, and a coil controlling said disengageable mechanical connection and controlled by a pair of said control switches.

45 3. The combination with a plurality of main switches, of a motor, a disengageable mechanical connection between said motor and each of said main switches for moving the same to normal position, a pair of motor control switches for each of said main switches, one control switch of each of said pairs closed when one of said main switches is in abnormal position, the second control switch of a pair connected in series with the other 50 control switch of the pair and closed when another of said main switches is in abnormal position, whereby said motor cannot be energized to actuate one of said main switches to normal position when another of 55 said main switches is in normal position, and an operator's switch having a plurality of positions in each of which it controls said motor through one of said pairs of motor control switches.

65 4. The combination with a plurality of

main switches, of a motor, a disengageable mechanical connection between said motor and each of said main switches for moving the same to normal position, a pair of motor control switches for each of said main switches, one control switch of each of said pairs closed when one of said main switches is in abnormal position, the second control switch of a pair connected in series with the other control switch of the pair and 70 closed when another of said main switches is in abnormal position, whereby said motor cannot be energized to actuate one of said main switches to normal position when another of said main switches is in normal 75 position, a coil controlling said disengageable mechanical connection and controlled by a pair of said control switches, and an operator's switch having a plurality of positions in each of which it controls said motor 80 and one of said coils through one of said pairs of motor control switches.

5. The combination with a plurality of switches, of a motor, a worm for each of said switches driven by said motor, a gear 90 for driving each of said switches and adapted to be driven by said worm, means for actuating said worm into engagement with its gear, and means actuated by one of said gears for preventing engagement of 95 a worm with another of said gears.

6. The combination with a plurality of switches, of a motor, a worm for each of said switches driven by said motor, a gear for driving each of said switches and 100 adapted to be driven by said worm, means for actuating said worm into engagement with its gear, means actuated by one of said gears for preventing engagement of a worm with another of said gears, and a member 105 preventing engagement of a worm with its gear when another worm is moved by said worm actuating means into engagement with its gear.

7. The combination with a plurality of switches, of a motor, a worm for each of said switches driven by said motor, a gear for driving each of said switches and adapted to be driven by said worm, means for actuating said worm into engagement 115 with its gear, means actuated by a gear when driven by its worm for preventing engagement of another worm with its gear and for preventing movement of said last named gear, and a member preventing engagement of a worm with its gear when another worm is moved by said worm actuating means into engagement with its gear.

8. The combination with a plurality of switches, of a motor, a disengageable mechanical connection intervening between each of said switches and said motor, said disengageable mechanical connection comprising driving and driven members, and means actuated by one of said driven members for 125 130

preventing movement of another of said driven members.

9. The combination with a plurality of switches, of a motor, a disengageable mechanical connection intervening between each of said switches and said motor, said disengageable mechanical connection comprising driving and driven members, and means actuated by the driven member of one of said disengageable mechanical connections for preventing engagement between the driving and driven members of another disengageable mechanical connection.

10. The combination with a plurality of switches, of a motor, a disengageable mechanical connection intervening between each of said switches and said motor, said disengageable mechanical connection comprising driving and driven members, and means actuated by the driven member of one of said disengageable mechanical connections for preventing movement of the driven member and for preventing engagement between the said driven member and the driving member of another of said disengageable mechanical connections.

11. The combination with a plurality of switches, of a motor, a disengageable mechanical connection intervening between each of said switches and said motor, said disengageable mechanical connection comprising driving and driven members, means actuated by one of said driven members for preventing movement of another of said driven members, and a member preventing simultaneous engagement of the driving members with their driven members of said disengageable mechanical connections.

12. The combination with a plurality of switches, of a motor, a disengageable mechanical connection intervening between each of said switches and said motor, said disengageable mechanical connection comprising driving and driven members, means actuated by the driven member of one of said disengageable mechanical connections for preventing engagement between the driving and driven members of another disengageable mechanical connection, and a member preventing simultaneous engagement of the driving members with their driven members of said disengageable mechanical connections.

13. The combination with a plurality of switches, of a motor, a disengageable mechanical connection intervening between each of said switches and said motor, said disengageable mechanical connection comprising driving and driven members, means actuated by the driven member of one of said disengageable mechanical connections for preventing movement of the driven member and for preventing engagement between the said driven member and the driving member of another of said disengageable mechanical

connections, and a member preventing simultaneous engagement of the driving members with their driven members of said disengageable mechanical connections.

14. The combination with a plurality of switches, a motor, a disengageable mechanical connection intervening between each of said switches and said motor, said disengageable mechanical connection comprising a worm gear and a worm movable with respect to each other, and means actuated by a worm gear for preventing rotation of a worm gear of another of said disengageable mechanical connections.

15. The combination with a plurality of switches, a motor, a disengageable mechanical connection intervening between each of said switches and said motor, said disengageable mechanical connection comprising a worm gear and a worm movable with respect to each other, and means actuated by a worm gear for preventing engagement between the worm and gear of another of said disengageable mechanical connections.

16. The combination with a plurality of switches, a motor, a disengageable mechanical connection intervening between each of said switches and said motor, said disengageable mechanical connection comprising a worm gear and a worm movable with respect to each other, and means actuated by a worm gear for preventing rotation of the worm gear and for preventing engagement therewith of the worm of another of said disengageable mechanical connections.

17. The combination with a plurality of switches, a motor, a disengageable mechanical connection intervening between each of said switches and said motor, said disengageable mechanical connection comprising a worm gear and a worm movable with respect to each other, means actuated by a worm gear for preventing rotation of a worm gear of another of said disengageable mechanical connections, and a member preventing simultaneous engagement of the worms with their worm gears of said disengageable mechanical connections.

18. The combination with a plurality of switches, a motor, a disengageable mechanical connection intervening between each of said switches and said motor, said disengageable mechanical connection comprising a worm gear and a worm movable with respect to each other, means actuated by a worm gear for preventing engagement between the worm and gear of another of said disengageable mechanical connections, and a member preventing simultaneous engagement of the worms with their worm gears of said disengageable mechanical connections.

19. The combination with a plurality of switches, a motor, a disengageable mechanical connection intervening between each of

said switches and said motor, said disengageable mechanical connection comprising a worm gear and a worm movable with respect to each other, means actuated by a 5 worm gear for preventing rotation of the worm gear and for preventing engagement therewith of the worm of another of said disengageable mechanical connections, and a member preventing simultaneous engagement 10 of the worms with their worm gears of said disengageable mechanical connections.

20. The combination with a plurality of switches, a motor, a disengageable mechanical connection intervening between each of 15 said switches and said motor, said disengageable mechanical connection comprising a worm and a worm gear movable with respect to each other, a member movable to 20 position to prevent rotation of a worm gear, and a cam driven by another of said worm gears for actuating said member.

21. The combination with a plurality of switches, a motor, a disengageable mechanical connection intervening between each of 25 said switches and said motor, said disengageable mechanical connection comprising a worm and a worm gear movable with respect to each other, a member movable to 30 position to prevent movement of a worm into engagement with its worm gear, and a cam on another of said worm gears for actuating said member.

22. The combination with a plurality of 35 switches, a motor, a disengageable mechanical connection intervening between each of said switches and said motor, said disengageable mechanical connection comprising a worm and a worm gear movable with 40 respect to each other, a member movable to position to prevent rotation of a worm gear, a cam driven by another of said worm gears for actuating said member, and means for returning said member to normal position.

23. The combination with a plurality of 45 switches, a motor, a disengageable mechanical connection intervening between each of said switches and said motor, said disengageable mechanical connection comprising a worm and a worm gear movable with 50 respect to each other, a member movable to position to prevent movement of a worm into engagement with its worm gear, a cam on another of said worm gears for actuating 55 said member, and means for returning said member to normal position.

24. The combination with a plurality of switches, of a worm and a worm gear disengageable from each other for actuating 60 each switch, a motor for driving said worms, a pivoted lever having abutments engaging the worm and its gear for holding said worm from engagement with its gear and holding 65 said gear against rotation, and means actu-

ated by another of the gears for actuating 65 said lever to free said worm and its gear.

25. The combination with a plurality of switches, of a worm and a worm gear disengageable from each other for actuating each switch, a motor for driving said worms, a 70 pivoted lever having abutments engaging the worm and its gear for holding said worm from engagement with its gear and holding said gear against rotation, a lever connected with said first named lever, and means upon 75 another of said gears for actuating said last named lever.

26. The combination with a plurality of electric switches, of actuating members therefor, the actuating member of one of 80 said switches comprising a worm gear, a worm for driving the same, a member for locking said worm gear against rotation, and means actuated by the actuating member of another of said switches for actuating 85 said locking member to release said worm gear.

27. The combination with a plurality of electric switches, of actuating members therefor, the actuating member of one of 90 said switches comprising a worm gear, a worm for driving the same, a member for locking said worm gear against rotation, and means actuated by the actuating member of another of said switches for actuating 95 said locking member to release said worm gear after predetermined movement of said actuating member of said other switch.

28. The combination with a plurality of 100 electric switches, of actuating members therefor, the actuating member of one of said switches comprising a worm gear, a worm for driving the same and normally disengaged therefrom, means for locking said 105 worm gear against rotation and said worm in normal position, and means actuated by the actuating member of another of said switches for actuating said locking means to free said worm and said worm gear. 110

29. The combination with a plurality of switches, of a worm and worm gear disengageable from each other for actuating each switch, means for locking the worm gear of one switch against rotation, and means actuated by the worm gear of another switch for actuating said locking means to free said first named worm gear. 115

30. The combination with a plurality of switches, of a worm and worm gear disengageable from each other for actuating each switch, means for locking the worm gear of one of said switches against rotation and the worm from engagement therewith, and means actuated by the worm gear of another 125 switch for actuating said locking means to free the worm gear and worm of said one switch. 120

31. The combination with a plurality of switches, of movable actuating members therefor, means for locking the actuating member of one of said switches against actuation, means actuated by the actuating member of another of said switches to actuate said locking means to free said first named actuating member, and a motor for driving said actuating members. 65
- 10 32. The combination with a plurality of switches, of movable actuating members therefor, means for locking the actuating member of one of said switches against actuation, means actuated by the actuating member 70
- 15 of another of said switches to actuate said locking means to free said first named actuating member, a motor for driving said actuating members, and a motor control switch closed upon completion of movement 75
- 20 of one of said switches by said motor to allow said motor to actuate another of said switches. 80
33. The combination with a plurality of electric switches, of actuating members 85
- 25 therefor, the actuating member of one of said switches comprising a worm gear, a worm for driving the same, a member for locking said worm gear against rotation, means actuated by the actuating member of 90
- 30 another of said switches for actuating said locking member to release said worm gear, and a motor for driving said actuating members. 95
34. The combination with a plurality of electric switches, of actuating members 100
- 35 therefor, the actuating member of one of said switches comprising a worm gear, a worm for driving the same, a member for locking said worm gear against rotation, 105
- 40 means actuated by the actuating member of another of said switches for actuating said locking member to release said worm gear, a motor, and a motor control switch closed upon completion of movement of one of said 110
- 45 switches by said motor to allow said motor to actuate another of said switches. 115
35. The combination with a plurality of switches, of a worm and worm gear disengageable from each other for actuating each 120
- 50 switch, means for locking the worm gear of one switch against rotation, means actuated by the worm gear of another switch for actuating said locking means to free said first named worm gear, and a motor for 125
- 55 driving said actuating members. 130
36. The combination with a plurality of switches, of a worm and worm gear disengageable from each other for actuating each switch, means for locking the worm gear of 135
- 60 one switch against rotation, means actuated by the worm gear of another switch for actuating said locking means to free said first named worm gear, and a motor control switch closed upon completion of movement
- of one of said switches by said motor to allow said motor to actuate another of said switches. 140
37. The combination with a plurality of switches, of a worm and worm gear disengageable from each other for actuating each 145
- 70 switch, means for locking the worm gear of one of said switches against rotation and its worm from engagement therewith, means actuated by the worm gear of another switch for actuating said locking means to free the 75
- worm gear and worm of said one switch, and a motor for driving said actuating members. 80
38. The combination with a plurality of switches, of a worm and worm gear disengageable from each other for actuating each 85
- 80 switch, means for locking the worm gear of one of said switches against rotation and its worm from engagement therewith, means actuated by the worm gear of another switch 90
- for actuating said locking means to free the worm gear and worm of said one switch, and a motor control switch closed upon completion of movement of one of said switches by said motor to allow said motor to actuate another of said switches. 95
39. The combination with a switch, of actuating means therefor, a plurality of switches, an actuating member for each of 100
- said switches, means normally locking each 105
- of said actuating members against actuation, said locking means of one of said switches actuated after predetermined movement of said actuating means of said first named 110
- switch for freeing the actuating member of 115
- said one of said switches, said locking means of another of said switches actuated after predetermined movement of said actuating member of said one of said switches for freeing the actuating member of said other of said switches, a motor for actuating the 120
- actuating members of said switches, and a motor control switch closed upon completion of movement of one of said switches by said motor to allow said motor to actuate another 125
- of said switches. 130
40. The combination with a switch, of actuating means therefor, a plurality of switches, an actuating member for each of 135
- said switches, means normally locking each 140
- of said actuating members against actuation, said locking means of one of said switches actuated after predetermined movement of said actuating means of said first named 145
- switch for freeing the actuating member of 150
- member of said one of said switches, said locking means of another of said switches actuated after predetermined movement of said actuating member of said one of said switches for freeing the actuating member of said other of said switches, a motor for 155
- actuating the actuating members of said switches, a motor control switch closed upon

completion of movement of one of said switches by said motor to allow said motor to actuate another of said switches, and a second motor control switch controlling said 5 motor closed upon movement of said first named switch by its actuating means.

41. The combination with a switch, of actuating means therefor, a plurality of switches, an actuating member for each of 10 said switches, means normally locking each of said actuating members against actuation, said locking means of one of said switches actuated after predetermined movement of said actuating means of said first named 15 switch for freeing the actuating member of said one switch, said locking means of another of said switches actuated after predetermined movement of said actuating member of said one of said switches for freeing 20 the actuating member of said other of said switches, a motor for actuating the actuating members of said switches, and a motor control switch closed upon movement of said first named switch by its actuating means.

25 42. The combination with a switch, of means for actuating the same, a plurality of switches, motive means for actuating the same, a switch controlling said motive means for actuating one of said switches closed 30 upon movement of said first named switch by its actuating means, and a second switch controlling said motive means for actuating another of said switches closed upon actuation 35 of said one of said switches by said motive means.

43. The combination with a switch, of means for actuating the same, a plurality of switches, a motor for actuating the same, a disengageable mechanical connection between 40 said motor and each of said switches, a switch controlling said motor for actuating one of said switches closed upon actuation of said first named switch by its actuating means, a second switch controlling said 45 motor for actuating another of said switches closed upon actuation of said one of said switches by said motor, electro-responsive means controlling said disengageable mechanical connections, and an operator's control switch controlling said electro-responsive means.

44. The combination with a switch, of means for actuating the same, a plurality of switches, a motor for actuating the same, a 55 disengageable mechanical connection between said motor and each of said switches, a switch controlling said motor for actuating one of said switches closed upon actuation of said first named switch by its actuating means, a second switch controlling said 60 motor for actuating another of said switches closed upon actuation of said one of said switches by said motor, electro-responsive means controlling said disengageable mechanical connections, and an operator's control 65 switch controlling said electro-responsive means.

trol switch controlling said electro-responsive means and controlling said motor through said motor control switches.

45. The combination with a switch, of means for actuating the same, a plurality of 70 switches, motive means for actuating the same, a switch controlling said motive means for actuating one of said switches closed upon movement of said first named switch by its actuating means, a second switch controlling said motive means for actuating another of said switches closed upon actuation of said one of said switches by said motive means, means for restraining said switches, and means for actuating said restraining 80 means to free said switches in response to movement of said first named switch.

46. The combination with a switch, of means for actuating the same, a plurality of 85 switches, motive means for actuating the same, a switch controlling said motive means for actuating one of said switches closed upon movement of said first named switch by its actuating means, a second switch controlling said motive means for actuating another of said switches closed upon actuation of said one of said switches by said motive means, means for restraining said switches in position to which actuated by said motive means, and means for actuating said restraining means to free said switches upon movement of said first named switch to abnormal position.

47. The combination with a switch, of means for actuating the same, a plurality of 100 switches, motive means for actuating the same, a switch controlling said motive means for actuating one of said switches closed upon movement of said first named switch by its actuating means, a second switch controlling said motive means for actuating another of said switches closed upon actuation of said one of said switches by said motive means, means for restraining said first named switch in normal position to which 105 actuated by its actuating means, means restraining said switches in normal position to which actuated by said motive means, means for tripping said first named switch, said restraining means of said switches actuated to free said switches upon tripping of said first named switch.

48. The combination with a switch, of means for actuating the same, a plurality of 120 switches, motive means for actuating the same, a switch controlling said motive means for actuating one of said switches closed upon movement of said first named switch by its actuating means, a second switch controlling said motive means for actuating another of said switches closed upon actuation of said one of said switches by said motive means, means for restraining each of said switches in normal position to which actuated by said motive means, and means for 125 130

tripping the remainder of said switches when any of said switches is tripped.

49. The combination with a switch, of means for actuating the same, a plurality of switches, motive means for actuating the same, a switch controlling said motive means for actuating one of said switches closed upon movement of said first named switch by its actuating means, a second switch controlling said motive means for actuating another of said switches closed upon actuation of said one of said switches by said motive means, means for restraining each of said switches in normal position to which actuated by said motive means, means for tripping the remainder of said switches when any of said switches is tripped, means for restraining said first named switch in normal position to which actuated by its actuating means, and means responsive to movement of said first named switch to abnormal position for tripping one of said switches.

50. The combination with a switch, of a motor for actuating the same, a switch for controlling said motor, means for locking said control switch, electro-magnetic means for actuating said locking means to free said control switch, and a switch controlling said electro-magnetic means and whose position is determined by the position of said first named switch.

51. The combination with a switch, of a motor for closing the same, a switch controlling said motor, means for locking said control switch against control of said motor, electro-magnetic means controlling said locking means, and a switch controlling said electro-magnetic means closed when said first named switch opens.

52. The combination with a plurality of switches, of motors for closing the same, a switch for controlling said motors, means for locking said control switch against control of said motors, electro-magnetic means controlling said locking means, and switches in series with each other in the circuit of said electro-magnetic means, said switches being closed when said first named switches are open.

53. The combination with a plurality of switches, of motors for closing the same, means preventing simultaneous closure of said switches, a switch controlling said motors, means for locking said control switch, electro-magnetic means controlling said locking means, and switches in series with each other in the circuit of said electro-magnetic means closed when said first named switches are open.

54. The combination with a switch, of a gear for actuating the same, a worm for actuating said gear and disengageable therefrom, a motor for driving said worm, a manually operable member, and a disengag-

able connection between said manually operable member and said gear for actuating the same in one direction only.

55. The combination with a plurality of groups of switches, of means for preventing actuation of the switches of a group except in predetermined order of succession, and means preventing simultaneous actuation of switches of different groups to normal position.

56. The combination with a plurality of groups of switches, of means preventing simultaneous actuation of switches of different groups to normal position, means normally locking a plurality of switches in a group against actuation to normal position, and means for unlocking said switches in succession in response to previous actuation of another of the switches of the group to normal position, and means preventing simultaneous actuation to normal position of said other of said switches of the different groups.

57. The combination with a plurality of groups of switches, of means for locking a plurality of switches in each group against actuation to normal position, means for unlocking said switches in succession in response to previous actuation of another of the switches of the group to normal position, and means preventing simultaneous actuation to normal position of said other of said switches of the different groups.

58. The combination with a plurality of groups of switches, of a motor for actuating switches of different groups, means preventing simultaneous actuation of said switches by said motor, a motor for actuating other switches of each group, and means preventing the actuation of the switches of a group except in a predetermined order of succession.

59. The combination with a plurality of groups of switches, of means for preventing actuation of the switches of a group except in predetermined order of succession, means preventing simultaneous actuation of switches of different groups to normal position, means for locking said last named switches in normal position, and tripping means common thereto for tripping any of them which may be in normal position.

60. The combination with a plurality of groups of switches, of means for preventing actuation of the switches of a group except in predetermined order of succession, means preventing simultaneous actuation of switches of different groups to normal position, means for locking said last named switches in normal position, tripping means common thereto for tripping any of them which may be in normal position, means for locking the other switches of each group in normal position, and means for tripping them when the associated switch controlled by said tripping means moves to abnormal position.

61. The combination with a plurality of

groups of switches, of a motor for actuating switches of different groups, means preventing simultaneous actuation of said switches by said motor, a motor for actuating other switches of each group, means preventing the actuation of the switches of a group except in a predetermined order of succession, and an operator's switch having a plurality of positions for each of said 10 motors for controlling the same to actuate different of said switches.

62. The combination with a plurality of groups of switches, of a motor for actuating switches of different groups, means preventing simultaneous actuation of said switches by said motor, a motor for actuating other switches of each group, means preventing the actuation of the switches of a group except in a predetermined order of succession, 15 an operator's switch having a plurality of positions for each of said motors for controlling the same to actuate different of said switches, means for locking said operator's switch against actuation, and electro-magnetic means controlling said locking means.

63. The combination with a plurality of groups of switches, of a motor for actuating switches of different groups, means preventing simultaneous actuation of said switches by said motor, a motor for actuating other 30 switches of each group, means preventing the actuation of the switches of a group except in a predetermined order of succession, an operator's switch having a plurality of positions for each of said motors for controlling the same to actuate different of said switches, means for locking said operator's switch against actuation, electro-magnetic means controlling said locking means, and a plurality of switches movable in unison 35 respectively with switches in different groups preventing energization of said electro-magnetic means except when said switches in different groups are in abnormal position.

In testimony whereof I have hereunto 40 affixed my signature this 21st day of June, 1915.

WILLIAM M. SCOTT.
